MOLD

Karl S. Howard, Haverford, Pa., assignor to General Steel Castings Corporation, Granite City, Ill., a corporation of Delaware

Application September 12, 1946, Serial No. 696,518

5 Claims. (Cl. 22—134)

1

The invention relates to molds and particularly to molds for casting elongated objects, such as large engine crank shafts.

The main object of the invention is to produce large elongated castings of high quality and accuracy by providing that shrinkage due to cooling is uniform throughout the castings and that the shrinkage forces are substantially balanced so as not to distort the castings. This is accomplished by utilizing a plurality of heads positioned at different elevations and spaced angularly about the cavity axis. The heads are equidistant from the cavity axis and as close thereto as possible without interfering with the strength of the mold. A plurality of short sprues of equal length and cross sectional area lead from the heads to the cavity. Referring more particularly to the casting of an engine crank shaft, each sprue leads directly to a main bearing forming portion of the cavity and each head, with its sprues, is positioned at the side of the cavity opposite the associated crank pin forming portions to which that head feeds molten metal and at least some of these crank pin forming portions are arranged symmetrically about a plane passing through the axes of the associated head and the cavity. With this arrangement, the paths of flow from the heads to the associated crank pin forming portions of the cavity are equal in length and shrinkage forces are substantially uniform throughout the cavity.

Other objects will be apparent to those skilled in the art from the following description and accompanying drawings, in which:

Figure 1 is a top view of a mold constructed according to the invention.

Figure 2 is substantially a central vertical longitudinal section through the mold, all of the right hand side of the figure and that part of the left hand side below the break line A—A being taken on the line 2—2 of Figure 1, and the left hand side of the figure above the break line being taken on the line 2a—2a of Figure 1, except that for clearer illustration each crank arm and pin is shown as if the plane of the section passed through the arm center line and the pin axis and was projected on the plane of the line 2—2 or 2a—2a, respectively.

Figure 3 is a transverse horizontal section taken approximately on lines 3—3 of Figures 2 and 6.

Figure 4 is a transverse horizontal section taken approximately on lines 4—4 of Figures 2 and 7.

Figure 5 is a transverse horizontal section taken approximately on lines 5—5 of Figures 2 and 8.

Figures 6, 7 and 8 are vertical longitudinal sections taken approximately on lines 6—6, 7—7 and 8—8 of Figures 3, 4 and 5, respectively,

2

The mold comprises a rectangular box-like housing having sides A, B, C and D of substantially equal size attached rigidly together by bolts 50. The housing is attached to base E by bolts 51. Positioned within the housing are a series of baked sand sections 1—22, inclusive, mounted one on top of the other, section 1 being at the bottom of the housing and section 22 being at the top. Each of the sections has one or more openings or depressions arranged so that when the sections are assembled in the housing, the openings and depressions form an elongated vertically disposed cavity 52 similar in shape to the crank shaft to be cast and provide gates, risers and sprues, as described in detail below, for feeding the metal to the crank shaft cavity.

The sections are positioned in one corner of the housing with two sides of each section adjacent sides A and B. Sand 57 is rammed between the other two sides of each section and sides C and D of the housing. To facilitate assembly of sections 1—22 in the housing, side D preferably is constructed in two parts, D1 and D2. With lower part D2 assembled with the housing and with upper part D1 removed, sections 1—12 are inserted in the housing and sand 57 is rammed between sides C and D and the sections, preferably as the sections are installed. Upper part D1 then is assembled with the housing and the remaining sections 13—22 are installed and sand 57 is applied between these sections and sides C and D as described above.

Sections 1—22 form an inlet gate 23 which is connected by a plain gate 37 and step gates 38 and 39 to a blind head 24 in sections 1—8. Head 24 is connected by sprues 27, 28 and 29 to the crank shaft cavity at main bearings 1b, 2b and 3b, respectively, and molten metal from head 24 flows direct to these bearings and then through the associated crank arms to the corresponding crank pins 4a, 5a and 6a.

Inlet gate 23 is connected by step gates 40, 41, 42 and 43 to a blind head 25 in sections 7—16. Head 25 is connected by sprues 30, 31, 32 and 33 to the crank shaft cavity at main bearings 4b, 5b, 6b and 7b. Molten metal from head 25 forms the latter-mentioned main bearings and crank pins 4a, 5a, 6a and 7a and associated crank arms.

Inlet gate 23 is connected by step gates 44 and 45 to a blind head 26 in sections 15—20. Head 26 is connected by sprues 34 and 35 to the crank shaft cavity at main bearings 8b and 9b. Molten metal from head 26 forms the bearings 8b, 9b and 10b and crank pins 8a and 9a and associated crank arms. The upper end of the crank shaft cavity at bearings 10b is connected to an open riser 46 formed in sections 20—22.

Heads 24, 25 and 26 are positioned as close as possible to the cavity axis, which coincides

with the axis of the crank shaft, without unduly weakening the mold and are equidistant from the cavity axis, so that the sprues leading to the main bearings are all as short as possible and equal in length and the sprues are made equal in cross sectional area. Heads 24, 25 and 26 at the portions above the sprues 29, 33 and 35, respectively, curve outwardly away from the cavity so as not to interfere with adjacent crank pin forming portions of the cavity supplied by the next higher head or with riser 46. Head 24 is positioned at the side of the cavity 52 directly opposite crank pin 1a (Fig. 3). Crank pins 2a and 3a are symmetrically disposed about a plane passing through the axes of cavity 52 and head 24. Head 25 is positioned at the side of the cavity opposite crank pins 4a, 5a, 6a and 7a (Fig. 4) and directly opposite to head 24 though at a higher elevation. Crank pins 4a and 5a and crank pins 6a and 7a are symmetrically disposed about a plane passing through the axis of cavity 52 and head 25. Head 26 is positioned at the side of cavity 52 opposite crank pins 8a and 9a (Figure 5) and is spaced angularly from heads 24 and 25 and is positioned at a higher elevation than these heads.

This angular spacing of heads 24, 25 and 26 permits the use of disaligned vertical vents 54, 55 and 56 leading from heads 24, 25 and 26, respectively, to the atmosphere.

At the top of each blind head 24, 25 and 26 is a triangular-shaped core 58 extending across the top of the head to facilitate cleavage of the shrinking metal and prevent a vacuum forming in the head as the metal cools and shrinks.

To cast the crank shaft, molten metal is poured in inlet gate 23 and flows progressively through gates 31, 38 and 39 to head 24 and through sprues 27, 28 and 29 into the crank shaft cavity to main bearings 1b, 2b and 3b through associated crank arms and to crank pins 1a, 2a and 3a. Likewise molten metal flows from inlet gate 23 through step gates 40, 41, 42 and 43 to head 25 and through sprues 30, 31, 32 and 33 into the crank shaft cavity to main bearings 4b, 5b, 6b and 7b, then through associated crank arms to crank pins 4a, 5a, 6a and 7a. Also molten metal flows from inlet gate 23 through step gates 44 and 45 into head 26 and thence through sprues 34 and 35 into the crank shaft cavity to bearings 8b and 9b and then through associated crank arms and to crank pins 8a, 9a, and bearing 10b. As additional metal is fed into gate 23, the metal rises in the crank shaft cavity into riser 46. As the metal cools and shrinks, heads 24, 25, 26 and riser 46 supply metal to the crank shaft cavity to prevent formation of airpockets in the crank shaft casting.

A mold of the kind described produces large elongated castings of high quality and accuracy and the shrinkage due to cooling is uniform throughout the castings.

The details of the above-described structure may be varied from those shown without departing from the spirit of the invention and the exclusive use of those modifications coming within the scope of the claims is contemplated.

What is claimed is:

1. A mold for casting a crank shaft having aligned main bearings and offset crank pins, comprising contiguous mold sections defining a metal-receiving mold cavity corresponding in shape to the crank shaft to be cast with the longitudinal axis of the cavity upright, and a plurality of feeding heads equidistant from the cavity axis and each having sprues arranged to feed metal to said

cavity through selected main bearing portions of the cavity, said feeding heads being positioned at different elevations and being spaced from each other angularly about the cavity axis.

5. A mold for casting a crank shaft having aligned main bearings and offset crank pins, comprising contiguous mold sections defining a metal-receiving mold cavity corresponding in shape to the crank shaft to be cast with the longitudinal axis of the cavity upright, and a plurality of feeding heads having sprues for feeding metal to said cavity, said feeding heads being spaced from each other angularly about the cavity axis and each of said feeding heads being positioned 10 on the side of the cavity axis opposite to its associated crank pin portions of the cavity.

15. A mold for casting a crank shaft having main bearings, crank arms and pins, comprising contiguous sections defining a mold cavity corresponding in shape to the crank shaft to be cast with the longitudinal axis of the cavity upright, and a plurality of feeding heads having sprues to feed molten metal through selected main bearing portions of the cavity to the crank arm and pin portions of the cavity, said feeding heads 20 being substantially equidistant from the cavity axis and spaced from each other angularly about the cavity axis and said feeding heads being positioned so that the associated crank pin portions 25 of the cavity are symmetrically disposed about a plane passing through the axes of the cavity and the associated feeding head.

30. A mold for casting a crank shaft, comprising contiguous mold sections defining a metal receiving cavity corresponding in shape to the crank shaft to be cast with the longitudinal axis of the cavity upright, a plurality of feeding heads having sprues for feeding metal to said cavity, said feeding heads being positioned at different elevations and being spaced from each other angularly about the cavity axis, and an inlet gate 35 corresponding in length to the crank shaft cavity and having a plurality of connecting gates for feeding molten metal to the feeding heads.

35. A mold for casting a crank shaft having aligned main bearings and offset crank pins, comprising contiguous mold sections defining an inlet gate extending substantially the full depth of the mold, a plurality of feeding heads positioned at different elevations and spaced from one another, a plurality of step gates connecting said feeding heads to said inlet gate, a metal receiving mold cavity corresponding in shape to the crank shaft to be cast and positioned with its axis upright and equidistant from said feeding heads, and a plurality of sprues all connecting said feeding heads to different main bearing portions of the cavity.
